UNITED STATES PATENT OFFICE

HENRY ALLEN AVERY, OF GROTON, NEW YORK, ASSIGNOR TO L C SMITH & CORONA
TYPEWRITERS INC., OF SYRACUSE, NEW YORK, A CORPORATION OF NEW YORK

TYPEWRITING MACHINE

Application filed April 20, 1928. Serial No. 271,499.

This invention relates to improvements in typewriting machines, and has for its object to provide an efficient key-operated mechanism for vibrating the inked ribbon of a 5 visible writing typewriting machine.

One feature of the invention is the provision of a compact ribbon guide vibrating mechanism consisting of few parts of light weight especially suitable for use in a small 10 and relatively flat portable typewriting machine having a type-bar-actuated universal bar.

Another feature of the invention is the provision of a simple and efficient ribbon vibrating mechanism settable to impart two 15 different extents of throw to a bichrome ribbon and to render the mechanism ineffective to vibrate the ribbon.

Another feature of the invention is the provision of a simple and efficient mechanism 20 for vibrating a ribbon guide for a bichrome ribbon shiftable with the platen of a typewriting machine having a case-shifting platen carriage.

Another feature of the invention is the provision of effective means for preventing 25 accidental overthrow of the ribbon, when using either zone of the ribbon, in connection with vibrating mechanism for imparting two different extents of throw to a bichrome 30 ribbon.

Another feature of the invention is the provision of a compact and efficient type-bar-actuated mechanism for vibrating a ribbon 35 guide to cover the printing point with either zone of a bichrome ribbon, and the provision of such a mechanism for use with a machine having a case-shifting platen so constructed and arranged that the vibratory guide will 40 shift bodily with the platen and have a uniform throw for each zone whether the platen be in upper or lower case position. Other features and advantages will appear from the following description.

Parts of the improvements may be used 45 without the others, and variations may be resorted to within the scope of the invention as defined by the claims.

In the accompanying drawings:

Fig. 1 is a longitudinal sectional view of

the machine, many of the parts being omitted to show more clearly the case shift mechanism, the bichrome shift and stencil adjustment mechanism for the ribbon vibrating means, and the mountings for certain parts 55 of the ribbon mechanism;

Fig. 2 a detail sectional view showing the mounting of the rotary escapement devices and associated parts of the ribbon mechanism;

Figs. 3, 4, 5 and 6 detail perspective views 60 of various parts of the ribbon mechanism;

Fig. 7 a rear view of the machine cocked up to a position in which the type bar segment is in a vertical plane and the carriage bed in a horizontal plane, the rear part of the main frame being broken away and the vibrator control means being set in "stencil" 65 position;

Fig. 8 a fragmentary bottom view of the 70 machine positioned as in Fig. 7;

Fig. 9 a perspective view showing part of the case shift frame, and also showing those 75 portions of the ribbon vibrating means and its adjusting means which are mounted on the shift frame, together with the elements connected directly therewith;

Figs. 10, 11 and 12 detail side elevations of similar portions of the ribbon vibrating means showing the positions thereof at the 80 end of the impression stroke of a type bar in each of the three adjustments of the bichrome shift and stencil control means;

Fig. 13 a fragmentary view of the machine, on an enlarged scale, looking from 85 the left hand side of the machine, parts of the machine being broken away to show the ribbon vibrating means in side elevation;

Fig. 14 a fragmentary bottom plan view 90 of the machine, on an enlarged scale, showing the ribbon vibrating means in normal position and set for covering the printing point with the upper zone of the ribbon, as in Fig. 13, the view being taken with the machine cocked as in Figs. 7 and 8;

Fig. 15 a front view of the ribbon vibrating means, set for use of the upper zone of the ribbon as in Figs. 13 and 14, the front arcuate 100 portion of the universal bar being broken

away, and the view being taken with the machine cocked as in Figs. 7 and 8;

Fig. 16 a section on the line 16—16 of Fig. 15, with parts of the escapement and fixed margin stop bracket broken away;

Fig. 17 a fragmentary view of the machine looking from the right, parts being broken away to show the ribbon vibrating means in side elevation, and the vibrating means being shown in normal position, and adjusted for vibrating the upper zone of the ribbon to the printing point; and

Fig. 18 a view similar to Fig. 17 showing the positions of the various parts at the end 15 of the printing stroke of a type bar.

The invention has been illustrated as embodied in the "Corona Four" typewriting machine which is constructed, except for the improved key-actuated ribbon-vibrating means and certain modifications of other parts associated therewith and hereinafter pointed out, substantially as shown and described in United States Letters Patent No. 1,700,827, No. 1,700,828, No. 1,700,829 and 25 No. 1,741,689.

The main frame of the machine comprises a front wall 10, a back wall 11, side walls 12, and a transverse partition wall 13 which is located in the rear portion of the main frame with its lower edge above the level of the lower edges of the other frame walls and inclines upward and rearward. A rearwardly inclined type-bar segment 14, having an arcuate recess 15 in its rear face, is held to the front face of wall 13 by suitable screws, with the usual arcuate pivot wire 16 therein lying in a plane parallel with said wall. An arcuate system of type bars 17 are fulcrumed on wire 16 and guided in the segment slots to strike on the upper front quarter of a platen 18. Character key levers 19 are fulcrumed at their rear ends on a pivot wire 20 held to a fulcrum plate 21 secured to the rear face of wall 13 by suitable fastening screws. The key levers extend downward behind wall 13 and then forward under said wall to the keyboard and are guided in a comb member 22 held to the main frame. The connection between each key lever and its associated type bar comprises a bell-crank lever 23 fulcrumed in a sub-lever segment 24 and connected with the type bar heel and key lever by links 25 and 26, respectively. Return springs 167 for the type bar actions connect key levers 19 with a spring anchor bar 166 on the main frame, hereinafter referred to.

The shift frame for the platen carriage 27 comprises a rearwardly and downwardly inclined carriage bed 28 having a pair of rigid downwardly and forwardly extending sheet metal guide members 29 fastened thereto at their upper ends adjacent opposite sides of the machine and connected by a transverse brace rod 30 adjacent their lower ends. The

carriage is mounted on the bed in rearwardly tilted position on suitable antifriction bearings, as shown, to travel transversely of the machine, and supports platen 18 above and in rear of the type bar pivots. The carriage and bed overlie the space between frame walls 11 and 13 and the guide members 29 extend down between said walls between cooperating guide members 31 held to the main frame side walls in upwardly and rearwardly inclined position, members 29 and 31 being provided with races in which are confined ball bearings, said members and races being so arranged as to guide the carriage and shift frame obliquely in a plane parallel with the plane of the segment, as in said application and machine before referred to.

As in the Corona Four machine, the shift frame is actuated by either of two shift key levers 33 fulcrumed on pivots 38 on brackets 39 held to frame walls 12, said levers having forked rear ends embracing studs 34 on the forward ends of the side arms 35 of a shift torsion and counterbalancing frame which comprises said arms 35 and a rock shaft 36 to which the arms are held. Shaft 36 is journalled on the frame walls 12 between wall 11 and the lower part of the shift frame, and studs 34 are engaged in rearwardly and downwardly extending slots 37 in members 29 of the shift frame. Brackets 39 also support a type bar rest 40.

Downward movement of the shift frame is limited by engagement of stops 41 on members 29 with adjustable stop screws 42 on brackets 43 held to frame walls 12. Upward movement of the shift frame is limited by the engagement of adjustable stop screws 44 on members 29 with stops 45 on brackets 43. The frame 35—36 is arranged to counterbalance the shift frame by connecting lugs 46 on arms 35 with the lower ends of counterbalancing springs 47 which are secured at their upper ends to arms 48 of brackets 43.

An arcuate sheet metal universal bar 49, adapted to be engaged and moved rearwardly by lugs 17^a on the type bars during the latter part of the printing strokes of the type bars, is located between segment 14 and wall 13 and is supported in a plane parallel with the planes of said wall and segment to vibrate in the segment recess 15 in a path substantially perpendicular to said planes and the rearwardly inclined plane in which the type bar pivot wire 16 in the segment lies. Universal bar 49 is carried at the forward ends of a pair of rearwardly and downwardly extending two-part sheet metal side arms comprising front sections 50 and 51 and rear sections 50^a and 51^a. Sections 50 and 51 are formed integrally with the universal bar, as shown, and extend through apertures 52 affording clearance openings through wall 13 and fulcrum plate 21. The front portions of sections 50^a and 51^a are rigidly but detachably

clamped to the rear portions of sections 50 and 51 by pairs of screws 54.

Sections 50^a and 51^a of the side arms are offset laterally inward at the rear ends of sections 50 and 51, and are provided with longitudinal guiding and supporting slots 53 in their offset rear portions extending perpendicular to the plane of the segment. These slots are open at their rear ends and correspond in width with the diameter of rock shaft 36 which extends therethrough and upon which the side arms are thus slidably supported and guided at their rear ends to reciprocate fore-and-aft of the machine. A transverse spacer bar 55 formed integrally with section 50^a forward of shaft 36 abuts the inner face of section 51^a.

The side arms extend from universal bar 49 through the shift frame and the shift torsion frame to points adjacent the lower edge of wall 11, and are supported and guided intermediate the universal bar and shaft 36 on fore-and-aft rocking arms 56 and 57, fixed at their lower ends on a short transverse rock shaft 58. Shaft 58 has trunnions 58^a journalled on the inner ends of bearing screws 59 threaded inward through the rear ends of a pair of arms 21^a which are formed integrally with fulcrum member 21 and extend rearward and downward to a point forward of shift frame rod 30 and close to the base line of the main frame. Arms 56 and 57 extend upward and rearwardly forward of shift frame rod 30 at a slightly less angle from the vertical than the wall 13 and shift frame and have pivot holes in their ends in which are engaged reduced pivot portions of pivot and spacing studs 61 and 64, the reduced outer supporting ends of the studs being swaged tightly in apertures in the arm sections 50 and 51, respectively, forward of arm sections 50^a and 51^a. Stud 64 has a reduced and headed extension 64^a extending inward from its pivot portion for supporting and guiding a part of the ribbon vibrating mechanism.

The universal bar is normally held at the forward limit of its movement against the front wall of recess 15 in the type bar segment 14 by a return spring, hereinafter described, and its extent of throw by universal bar contacting lugs 17^a on the type bars 17 is such that the pivot studs 61 and 64 and upper ends of rock arms 56 and 57 swing between points substantially equal distances at opposite sides of a plane through the axis of rock shaft perpendicular to the plane of the carriage bed and parallel with wall 13. The arrangement and movement of rock arms 56 and 57, together with the arrangement of slots 53 longitudinally of the side arms and perpendicular to the plane of wall 13, provides for supporting and guiding the universal bar 49 to vibrate obliquely to the horizontal plane of the machine in a path sub-

stantially perpendicular to the plane of the segment and its type bar pivot wire.

The escapement and line-locking mechanism are constructed as in the Corona Four machine, with the exceptions hereinafter pointed out, and need only be so far described as to permit a full understanding of the present invention. A sheet metal bracket 65 has its flat body part held by screws 66 against the bottom face of carriage bed 28 and extending across an opening 85 in said bed. A steel bushing 67 extends through, and is tightly swaged in, an opening in said body part of the bracket and is formed with a narrow cylindrical hub portion 67^a abutting the said bracket at its upper end, said hub portion being of less diameter than the lower end of the bushing to provide an annular seat 67^b parallel with said body part of the bracket for a line-lock member, hereinafter described, pivoted on said hub.

Bracket 65 is formed with rearwardly and downwardly extending side arms 68 and 69 carrying at their rear ends horizontal pivot screws 70 having reduced pivot ends engaged in bearing apertures in pendent pivot ears 72 and 73 formed at the ends of the flat body part of a sheet metal dog rocker 74. A rigid holding dog 75, formed on the forward edge of rocker 74, and a feeding dog 76 (pivoted on the rocker at 77 and controlled by a suitable spring and stop device), cooperate with a toothed escapement wheel 78 to control the feed of the carriage. Wheel 78 in the present construction is formed with a pendent hub 78^a and is fixed on the lower end of a shaft 79 journalled in bushing 67 and carrying a feed pinion 80 at its upper end meshing with a rack 81. Rack 81 lies between the carriage base plate and carriage bed and is formed integrally with a portion of the carriage base plate as in the Corona machine. The carriage 27 is normally urged toward the left by the usual spring drum 82 which is held to the carriage bed at 83 and is connected in the usual way by a suitable cable with the carriage. Pinion 80 is adapted to pass through opening 85 in the bed 28, so that bracket 65 together with the parts mounted thereon is removable from and attachable to the bed as a unitary assemblage.

In the present construction the escapement shaft is prolonged downward to a point above the level of the universal bar side arms and is formed with a circumferential groove 86 closely adjacent its lower end in which is engaged a bendable horseshoe shaped key 87 between which and the lower end of the escapement wheel hub is confined the main body part of a lever forming part of the ribbon vibrating means, which lever as herein-after described is pivotally supported on the shaft 79 and the hub 78^a of the escapement wheel 78.

In the present construction also the prolonged portion of the shaft below the bushing is formed with longitudinal grooves 88 into which are firmly screwed the inner end of set screws 89, threaded through the hub of the escapement wheel, for holding the wheel to the shaft. The outer ends of screws 89 are countersunk within the periphery of the hub 78^a which is free from other projections and is cylindrical.

Dog rocker pivot ear 73 is formed with a forwardly extending stop arm 90 formed with an upstanding rearwardly facing hook lug 90^a the upper end of which normally abuts the bottom face of bracket 65 adjacent the inner side of bracket arm 69 to arrest return movement of dog rocker 74 under the pull of the rocker return spring 91. Spring 91 is connected at its rear end with a lug 92 projecting laterally outward from the lower end of rocker pivot ear 72 and is connected at its forward end with a pendent lug 93 on bracket arm 68. The feeding dog 76 normally engages a tooth of the escapement wheel 78 with holding dog 75 above the plane of the wheel. The rocker is provided with an arm 94 depending from its pivot ear 73 and formed with an outwardly extending contact lug 95 at its lower end lying flatwise in a plane perpendicular to wall 13 and the path of movement of the shift frame. The rocker is adapted to be rocked through the medium of said arm 94 and lug 95, to disengage dog 76 and engage dog 75 with escapement wheel 78, by tappets 96 and 97 movable, respectively, with the type-bar-actuated universal bar 49, and a space bar (not shown); said tappets being located forward of lug 95 with their rear lug-contacting edges parallel with the path of shift of the shift frame.

Tappet 96 is rigid with and formed on the rear end of side arm 50 of the universal bar and, in the machine shown, is normally spaced slightly forward of lug 75. Tappet 97 is formed on the rear end of a bar 98, and is normally substantially engaged by lug 95, as shown. The bar 98 is guided to move rearward and downward upon depressions of the space bar, being provided with a downwardly inclined guide slot 99 in which engages a stud 100 projecting outward from rock arm 56, as in the machine hereinbefore referred to.

A plate 101 formed of sheet metal is held to the carriage bed 28 by screws 102 and 103 passing through a forwardly extending base flange formed on said plate and underlying the bed. Plate 101 extends up behind the rear raceway of the carriage where it is formed with a carriage stop lug 113^a.

A right hand margin stop 104 is mounted on the margin stop bar 105 carried by the platen carriage and is adjustable along said bar as in the Corona machines. Stop 104 is

formed with a pendent stop lug 104^a at its lower end adapted to engage and operate a line-locking member. The line-locking member comprises a sheet metal latch lever or pivoted plate 112 having its flat body part underlying bracket 65 and held flat against the bottom face of said bracket by the annular upwardly facing seat or shoulder 67^b on bushing 67, said plate having a slot 106 therein extending rearward from the forward edge of 75 said plate and rounded at its rear end so that the rear end and rear portions of the side walls of the slot hug the periphery of the hub section 67^a of the bushing. Slot 106 thus forms a pivotal bearing aperture in the plate 80 adapted to receive hub 67^a and open at one side so that the plate may be slipped edge-wise on and off its pivot.

Plate 112 is formed with a rearwardly facing notch 107 in its rear end, downwardly into which projects the thickened head of the right hand fastening screw 103 for plate 101, said screw head being of less diameter than the width of the notch 107 at the point where said screw head extends into the notch. The left hand wall of notch 107 forms a stop face normally held engaged with the head of screw 103 by coil spring 108, with the stop face formed by the opposite wall of said notch spaced from said screw head. Spring 108 in the present construction is connected at its rear end with the outer end of an integral arm 109 extending toward the right from the rear end of plate 112 to a point adjacent bracket arm 68, while the forward end of the spring is connected to an arm of the ribbon guide vibrating bell crank, herein-after described, to yieldably hold both of the members in normal position. Spring 108 not only normally holds plate 112 rocked toward the right, but also exerts a constant forward pull on said plate to prevent accidental detachment of the plate from its pivot hub.

Arm 109 is offset upward intermediate its ends in rear of plate 101 and formed with a stop lug 110 projecting rearward therefrom and having a straight rearwardly extending right hand edge normally in the path of travel of stop lug 104^a of margin stop 104. Plate 112 is formed with a latch arm 111 offset downward therefrom and normally extending rearward and to the left from the left hand edge of plate 112 and clearing the relatively thin head of fastening screw 102 of plate 101.

Arm 111 is normally located in rear of the recess or throat of the rearwardly facing hook lug 90^a on dog rocker arm 90 and is adapted to swing into said recess when plate 112 is rocked toward the left against the pull of spring 108 (until arrested by engagement of the right hand edge of notch 107 with the head of screw 103) through the engagement with lug 110 on member 112 of lug 104^a of 130

margin stop 104 as the carriage is fed toward the left. When this occurs, the dog rocker is positively locked in normal position so that the carriage cannot be fed farther toward the left. Since the dog rocker cannot tilt, if a character key is depressed, its connected type bar 17 will simply swing up to the position where the universal bar has moved slightly rearward and been arrested by tappet 96 striking lug 95 on the locked dog rocker. As the universal bar is thus arrested forward of its normal rearward limit of travel, it blocks the completion of the printing stroke of the type bar and thereby prevents making of superimposed impressions upon the work sheet. The line may be unlocked as in the Corona machine, by means not herein shown, and advance of the carriage continued until stop 104 strikes the fixed stop or lug 113^a on plate 101.

The ribbon vibrator, or reciprocatory ribbon guide, 113 is slidably guided on the type guide 114 to vibrate up and down in a plane parallel with the plane of the segment and the plane of case-shift movement of the platen. Type guide 114 is constructed and attached to wall 13 by screws as in the machine and applications before referred to, having a flat main body portion lying parallel with the plane of the segment and provided with a type bar guiding throat 115 at its upper end and a longitudinal slot 116 extending upward from its lower edge. Ribbon guide 113 lies behind the type guide and consists of a flat sheet metal plate provided at its upper end with ribbon guiding slots and intermediate its ends with angular guide lugs 117 embracing the sides of the type guide, all as in the machine referred to.

In the present construction, ribbon guide 113 is formed at its lower end with a central pendent tongue bent rearwardly at 118, and then bent successively forwardly, downwardly, and rearwardly to form a rearwardly and downwardly facing U-shaped socket 119. The front wall of socket 119 lies immediately forward of the plane of the front face of the type guide and in the same inclined plane as the inwardly bent forward ends of lugs 117 and is formed with lateral guide lugs 120 lying in the plane of said front wall and overlapping the front face of the type guide at opposite sides of slot 116.

Socket portion 119 of the ribbon guide slidably works in slot 116 to assist lugs 117 to hold the ribbon guide against lateral tilting, while lugs 117 and 120 on the one hand, and the flat main body of the ribbon guide on the other hand, work against opposite faces of the inclined flat body part of the type guide to maintain the ribbon guide in the plane of the segment during vibratory movement thereof.

A bichrome inked ribbon 121 is reeled on the ribbon spools 122 and threaded through guide slots in vibrator 113. The spools and

their pawl and ratchet rotating devices are mounted on brackets 123 held to carriage bed 28 at opposite sides of the machine as in the Corona Four machine.

Ribbon vibrator 113 is reciprocated and is also supported to shift bodily in unison with the platen during case shifting, by a vibrator actuating bellcrank 124 pivotally mounted in a bracket 126 detachably held to the bottom face of carriage bed 28 by screws 127. Bracket 126 takes the place of a similarly located bracket in the Corona machine and is formed at its front edge with a pair of upwardly and rearwardly inclined lugs 128 for supporting the line gauge and printing point indicator of the machine, but in the present construction the flat body part of the bracket is formed with a pair of integral pendent pivot lugs 125 for bellcrank 124 lying flatwise in fore-and-aft extending and transversely spaced planes and provided with bearing apertures for the shouldered pivot portion of pivot screws 129, the reduced threaded ends of which are screwed into threaded holes in the upper parts of pendent arms 130 and 131 of bell crank 124.

The bellcrank 124 is formed of sheet metal and consists of a transverse bar-like body part which is formed at its ends with the integral pendent arms 130 and 131, and is formed intermediate its ends with a forwardly extending integral arm 132 extending toward the type guide. Arm 132 has its front end bent to lie edgewise in a vertical plane and terminates in an enlarged bearing head 133 the top and bottom edges of which are rounded. Head 133 is engaged in socket portion 119 of the ribbon guide, thereby affording a separable rocking connection between the bell crank and the guide. Bellcrank arm 131 is bent horizontally outward below its pivot ear, and this outwardly bent arm portion is formed at its rear edge at its outer end with an integral pendent stop lug 134 lying flatwise in a transverse plane and normally held back against a fixed abutment on the shift frame, namely the front edge of the lug 93 on escapement bracket arm 68 to which the front end of dog rocker return spring 91 is anchored. The bellcrank is yieldably held in this normal position, with the ribbon guide lowered to retract the ribbon from in front of the impact point on the platen, by the spring 108 hereinbefore referred to, the front end of this spring being anchored to the horizontal portion of bellcrank arm 131 and its rear end to the arm 109 of the pivoted line-locking member 112 before described. Stop lug 134 is bendable fore-and-aft of the machine to adjust the normal fore-and-aft position of pendent arm 130 of the bellcrank 124.

Bellcrank 124 is rocked in opposition to spring 108 by an actuating lever 135 to cause the ribbon to cover the printing point. This

lever is an upstanding and fore-and-aft rockable lever having a single arm, is axially shiftable to either of three different positions relatively to the pendent arm of the bell-crank, and has a rocking movement of the same amplitude about its axis in each of said positions. The axial setting of lever 135 determines the amplitude of throw of the bell-crank, which is nil in one setting for writing stencils, short in another setting for causing the upper (usually black) zone of the ribbon to cover the printing point, and longer in the third setting for causing the lower (usually red) zone of the ribbon to cover the printing point.

Lever 135 is stamped from sheet metal and has its main body portion provided at its upper end with a stop arm 136 extending transversely of the machine in rear of the hub 78^a of the escapement wheel 78 and provided at its lower end with a tail piece 137 terminating in rear of brace rod 30 of the carriage shift frame. The intermediate portion of the lever 135 is widened and of U-shape in plan view, affording a broad flat contact wall 138 for an actuating tappet and a pair of forwardly extending walls 139 and 140 with the forward edges of which are connected by integral bendable tongues of metal, a pair of fore-and-aft bendable slotted ears 141 and 142 lying flatwise in the planes of the walls 139 and 140 respectively and connected with said walls by said tongues intermediate the upper and lower ends of the ears.

The intermediate body portion of the lever is formed with a pair of pendent transversely spaced guiding and pivot ears 143 and 144 below walls 139 and 140, respectively, lying in fore-and-aft planes and provided with circular bearing holes 145 through which brace rod 30 passes loosely, affording a sliding and pivotal mounting for lever 135 at its lower end on the shift frame. Lever 135 is spring retracted, as hereinafter described, with stop arm 136 spaced rearward from hub 78^a, and is rocked forwardly by a two-armed tappet lever 146. Lever 146 is formed of sheet metal and has its flat body portion 146 fitted between the flat lower end of escapement wheel hub 78^a and the escapement shaft key 87 and provided with a bearing aperture 147 through which the escapement shaft 79 extends and also with an integral upwardly offset bearing ring 148 encircling the upper end of hub 78^a, thus affording a steady bearing for the lever for rocking about said shaft and hub in a plane perpendicular to the plane of movement of the case-shift frame. Ring 148 is connected with the body part of lever 146 by a single web 149 located forward of hub 78^a, so that the double lever bearing does not obstruct movement of stop arm 136 on lever 135 into and out of engagement with said hub.

The body part of lever 146 is formed with a tappet-carrying arm 150 extending toward

the left hand side of the machine and formed with an integral pendent tappet 151 disposed edgewise in a fore-and-aft plane behind contact wall 138 of lever 135, said tappet preferably having a forwardly projecting rounded nose portion contacting said wall, as shown. The body part of lever 146 is also formed with an arm 152 extending toward the right hand side of the machine through a slot 153 in a fore-and-aft reciprocable ribbon actuator 154 which is so mounted in the main frame as not to partake of the case-shift movement of the shift frame.

Ribbon actuator 154 consists of a sheet metal bar disposed edgewise in a vertical plane and having the transverse slot 153 intermediate its ends, open at the top and extending parallel with the plane of shift of the shift frame, and also having the longitudinal open-ended slots 155 and 156 at its front and rear ends, respectively, extending parallel with the path of movement of the universal bar and perpendicular to the path of shift of the shift frame. Actuator bar 154 is also formed with an integral pendent arm 157 adjacent its front end extending down between rod 30 and shaft 58. The slotted forward end 155 of ribbon actuator 154 is guided and supported in and by the circumferentially grooved inner end 64^a of pivot stud 64 carried by universal bar side arm section 51, and the slotted rear end of the rearwardly and downwardly extending actuator is guided and supported in a circumferential groove 158 in the rock shaft 36 forming part of the shift torsion frame.

The slots and supports are so arranged that actuator bar 154 is movable endwise rearwardly and downwardly by the universal bar through the medium of stud 64 in a path perpendicular to the path of shift of the shift frame. The described method of mounting and actuating bar 154 permits rearward movement of the bar either by, or independently of, the universal bar, and also affords a simple mounting and operating means for the actuating bar.

In the machine shown, the ribbon feeding and reversing devices are also actuated from bar 154, and the capacity for independent movement of bar 154 is utilized in connection with the typing of accent characters, by means not shown herein. The ribbon actuator 154 and universal bar 49 are returned to normal position by a return spring 159 connected with the actuator shaft 164 for the ribbon spool driving and ribbon feed reversing devices of the machine, said return being assisted, except during stencil writing, by the common return spring 108 for the vibrator actuating bellcrank 124 and line-locking lever 112. The ribbon feeding and reversing devices and actuating shaft 164 therefor are constructed as in the machine

and applications referred to and need only be briefly described.

The ribbon spools 122 rotate with ratchets 160 on the brackets 123 held to the carriage bed 28, said ratchets being driven by pawls 161 pivoted on brackets 123 and connected by links 162 with upstanding rock arms 163 fixed on the actuating rock shaft 164. Shaft 164 is journaled on the main frame and lies under wall 13, and the left hand rock arm 163 is extended downward below the shaft to provide a pendent rock arm 165 connected by the return spring 159 (above referred to) with a spring anchor bar 166 mounted in the main frame of the machine to which the type bar action return springs 167 are also connected. Arms 163 carry tappet hooks 168 at their upper ends for actuating the ribbon-abutment settable trip devices 169 to throw one pawl 161 out of action and the other pawl 25 into action by the pawl-controlling means of the Corona machine not herein shown. About midway its ends rock shaft 164 is provided with a pendent rock arm 170 for oscillating the shaft at the type strokes.

All the foregoing parts of the ribbon feeding and reversing means are constructed as in the Corona Four machine and the applications referred to above. In the present construction, pendent rock arm 170 is positively connected by a rigid fore-and-aft extending wire link 171 with the outwardly bent lower end of pendent arm 157 of the reciprocable ribbon actuator bar 154, said link 171 extending under one of the reduced trunnion portions 58^a of rock shaft 58 and lying substantially at the level of the base line of the main frame.

It will be obvious that spring 159 normally rocks shaft 164 in a direction to cause link 171 to draw actuator bar 154 forward, and that said bar, through engagement of the rear end of slot 155 with part 64^a of stud 64 will push the universal bar forward until return movement of these parts under the influence of spring 159 is arrested by the front edge of the arcuate universal bar 49 abutting the front wall of the recess 15 in type bar segment 14, which will serve as a stop to determine the normal positions of the parts of the ribbon mechanism. Since tappet lever 146 is interlocked with actuator 154 its normal position is also fixed by this arrest of the universal bar. The normal return position of bellcrank actuating lever 135 is also determined by this arrest of the universal bar through abutment of wall 138 of the lever with tappet 151 on tappet lever 146.

Lever 135 is axially slidable on rod 30 to disconnect it from the bellcrank 124 at one point, and either leave it disconnected for stencilling, or to reconnect it with the bellcrank at another point. The lever is guided by rod 30 and tappet 151 during axial sliding adjustment thereof, and in order to hold the

lever back against the tappet a light spring 172 is provided. In the construction shown, spring 172 is connected at one end with an eye 173 punched rearward from tail piece 137 of lever 135 and extends upward and rearward therefrom to the transverse body part of dog rocker 74 to which its upper end is attached by passing its upper hooked end about the web of metal between the rear edge of the rocker and one of the stop eyes 174 punched down from the rocker with which the pair of pivoted spring-connected feed-dog controllers of the Corona machine cooperate.

Spring 172 is preferably of light tension, only strong enough to hold up the lever 135 against the tappet and to return this lever, alone, during stencil writing, when the lever is disconnected from the bellcrank. Spring 172 is only very slightly stretched on the down strokes of the keys until tappet 96 picks up the dog rocker, after which the lever 135 and dog rocker 74 swing together in the same direction without appreciable tensioning of the spring during the remaining part of the down strokes of the keys. This arrangement, together with the light normal tension of the spring provides in a simple way for the before described sustaining of lever 135 during axial shifting, and return thereof during stencil operations, without adding an appreciable load to the ribbon vibrating means during normal operation of the machine.

The pendent arm 130 of vibrator actuating bellcrank 124 has rigidly attached thereto, adjacent its lower end, two laterally projecting short pins or studs 175 and 176 located different distances from the pivotal axis of the bellcrank and at different sides of arm 130, said pins having reduced portions passed through holes in arm 130 and headed over against the arm. The U-shaped or yoke-like body part of lever 135 embraces the lower end of arm 130 of the bellcrank, and wall portions 139 and 140 of this part of lever 135, with their attached slotted ears 141 and 142, are spaced apart sufficiently to clear the outer ends of both of the pins 175 and 176 when lever 135 is in its intermediate axially adjusted position. This yoke portion is of such depth fore-and-aft that wall 138 will not engage arm 130 of the bellcrank during stencil operations.

Lever 141 is formed with a slot 177 for receiving pin 175 when lever 135 is shifted toward the right from its neutral or stenciling adjustment position, and ear 142 is formed with a slot 178 for receiving pin 176 when lever 135 is shifted toward the left from neutral position. Ears 141 and 142 and their slots are preferably of the same shape and said ears and their coactive pins are preferably located different distances from the fulcrum of lever 135, as shown, so that when pin 175 is engaged with ear 141 the effective length of lever 135 is increased and the effec-

tive length of bellcrank arm 130 is decreased, whereas, when ear 142 is engaged with pin 176, the effective length of lever 135 is decreased and the effective length of arm 130 is increased, thus affording a compact arrangement for imparting the long and short throws of necessary extent to the vibrator bellcrank from an actuating lever having a short throw of constant amplitude imparted 5 by a type-bar-actuated universal bar which, in the machine shown, as is usual, is only moved by the type bars during the latter portion of the printing strokes of the type bars. Each of the slots 177 and 178 is enlarged or 10 widened at its forward edge at the lower end of the slot to provide a substantially circular lower end portion of a size substantially larger than the pin diameter to facilitate the engagement of the pins in the slots upon axial 15 adjustment of the lever 135, said slots each being of the same width as the diameter of the pins from a point directly above the normal point of engagement of the pins therein to their upper ends. 20

25 The contracted major portions of the slots are straight and made sufficiently long to prevent the pins from abutting the upper ends of the slots before stop 136 engages hub 78^a, while permitting such adjustment of the 25 slotted ears 141 and 142 and bendable stop 136 as may be necessary to give proper amplitudes of movement to the vibrator for using the two zones of the ribbon. The close fit of the pins in the contracted main portions of the slots, 30 effected as soon as the lever 135 starts forward, prevents the bell-crank from bounding upward and forward away from its actuating lever and prevents overthrow which would result from such bounding or continued movement of the bellcrank by acquired 35 momentum after lever 135 is arrested by its stop arm 136 striking the relatively stationary stop formed by hub 78^a of escapement wheel 78. The liability of such overthrow 40 of the bellcrank and vibrator is greater on the long throw of these parts in using the lower zone of the ribbon and, as due to slight inaccuracies in size of the pin and slot in manufacture, or to wear, it is possible that there 45 may exist sufficient play of the pin 175 in slot 177 to permit overthrow of the vibrator under the augmented momentum acquired on the long throw, I prefer to employ an auxiliary overthrow-preventing stop device for 50 the bellcrank effective only when the vibrating mechanism is set for this long throw. This auxiliary stop may, however, be omitted, if desired. 55

60 Said auxiliary overthrow preventing means comprises a movable stop 179, consisting of an integral lug extending forward and upward from the front edge of the transverse body part of bellcrank 124 and bendable up and down for purposes of adjustment, and a 65 fixed stop consisting of the bottom face of

the main body part of bracket 126. On the short throw of the vibrator, lug 179 (as shown in Figs. 10 and 18) does not move far enough to strike bracket 126, but said lug is adjusted so as to strike the bottom face of the bracket 70 adjacent the forward edge of the bracket (as shown in Fig. 11) on the long throw of the vibrator when stop arm 136 on lever 135 strikes hub 78^a of escapement wheel 78. 75

75 The color shift and stencil control means for axially adjusting lever 135 to vary the amplitude of throw of the vibrator 113 for using different zones of the ribbon, and to render the vibrator inactive for writing stencils, extends to the left hand side of the keyboard of the machine for convenient operation. The key lever guide comb 22 is formed at its ends with attachment lugs 180 abutting the inner faces of side walls 12 of the main frame and held thereto by pairs of screws 181 80 passed inward through the walls and threaded through the lugs. The inner ends of fastening screws 181 for lug 180 at the left hand end of the comb are also threaded through the rearwardly extending arm 182^a of an up-right sheet metal bracket 182 to detachably hold said bracket to the left hand frame wall 12. Arm 182^a extends through a notch or slot 22^a in comb 22, and the main body of bracket 182 extends upward flatwise alongside wall 12 forward of the comb and is formed at its upper end with an inwardly bent flange 183 disposed substantially horizontally. 90

95 Flange 183 is formed with a fore-and-aft extending slot 183^a having its inner edge provided with a central locking notch 184 and two end locking notches 185 and 186 which notches are adapted to receive the handle arm 187 of a sheet metal bell-crank hand lever. Lever arm 187 is spring tempered and normally bowed toward the right, to automatically spring into the locking notches, and extends up through slot 183^a, being provided at its upper end with a finger piece 188 for rocking the lever and for flexing it toward 100 the left out of the locking notches. 105

110 This hand lever is pivotally held to the lower end of bracket 182 at a point forward of the comb 22 by a transverse pivot screw 189, and has an arm 190 extending rearward through comb notch 22^a and then upward a short distance behind the comb. A sheet metal bar 191 is pivotally connected at its front end by a transverse pivot screw 192 with the free end of hand lever arm 190, and extends rearwardly under sub-lever segment 24 and over spring anchor bar 166 to a point under partition wall 13. Anchor bar 166 is held in slots in the forward ends of a pair of fore-and-aft adjustable sheet metal bars 193 115 clamped to arms 43^a, extending forward under wall 13 from brackets 43, by pairs of clamping screws 194 which pass through longitudinal slots in bars 193 and are threaded into the bracket arms 43^a, for adjusting the 120 125 130

10 tension of the type bar action return springs 167.

15 In the present construction, the rearmost one of the pair of screws 194 at the left hand side of the machine is shouldered between its head and the inner face of the adjacent bar 193 (see Fig. 8), and the rear end of bar 191 is provided with an open ended longitudinal slot 195 in its rear end through which said shouldered portion of the screw extends to 20 slidably support and guide the rear end of the bar 191 which is confined between the screw head and inner face of bar 193, said slot 195 extending rearward and downward so that bar 191 (guided by said slot and the upward and rearward extending arm 190 of the hand lever 187) will move obliquely substantially perpendicular to the plane of the shift frame when the hand lever is rocked.

25 In rear of sub-lever segment 24, arm 191 is formed with an integral upstanding finger 196, bendable fore-and-aft for adjustment purposes, to which is pivotally connected the forward end of a rigid wire link 197 which 30 extends rearward and downward under wall 13 to a point adjacent the lower end of the left hand shift frame member 29 where it is pivotally connected with the outwardly extending arm 198 of a sheet metal bellcrank 35 lever 199 pivoted on said shift frame member. As shown in Fig. 1, the link 197 is so arranged that its rear end will move, when the shift frame is shifted from one case position to the other, between points located equal distances below and above an oblique plane perpendicular to the plane of shift of the shift frame and passing through the point of connection of the forward end of the link with finger 196, so that the action of the hand lever 40 on the bell crank 199 will be the same in either case position of the shift frame and the adjustment of lever 135 will not be disturbed by case shift movements of the shift frame.

45 In the Corona machine previously referred to, the upper case stop screws 44 are carried by the outer ends of a pair of sheet metal bars 200 each fastened by two screws 201 to the under faces of lugs 202 stamped forward out of the main transverse body portions of the 50 shift frame members 29, said lugs lying flatwise in a plane perpendicular to the plane of movement of the shift frame. In the present construction, a simple and efficient mounting for bell-crank 199 on the shift frame is afforded by substituting a long shouldered pivot screw (indicated at 201^a) for the outer most one of the pair of fastening screws for the left hand stop carrying bar 200, the long bearing or shoulder portion of the screw 201^a 55 depending below bar 200 and lug 202 parallel with the path of shift of the shift frame, and by forming the middle portion of bellcrank 199 with two superposed pivot ears 203 through which said bearing portion of screw 60 201^a extends, the lower ear resting on the head

of the screw and the upper ear engaging under bar 200.

To the right of pivot ears 203, bellcrank 199 is provided with an arm 204 extending rearward through the aperture 205 in shift frame member 29, afforded by the stamping out of lug 202, and connected in rear of member 29 with lug 46 on the adjacent rock arm 35 of the shift torsion frame by a coil spring 206 which normally draws said arm toward the left until arrested by engagement of a stop lug 207 on said arm with the front face of member 29. A rigid wire link 208 connects the rear end of arm 204 of bellcrank 199 with the tail piece 137 of the axially adjustable actuating lever 135 for the ribbon vibrator operating bellcrank 124.

70 Link 208 is permanently bendable to vary its length for proper axial positioning of lever 135. Stop lug 207 is bendable fore-and-aft for purposes of adjustment and engages member 29 to prevent spring 206 from rocking bellcrank 199 far enough to cause the left hand side of lever 135 to bind or rub on the adjacent sectional side arm of the universal bar when the vibrating mechanism is set for the short throw of the ribbon vibrator. Spring 206 constantly tends to take up any slack in the operating train for adjusting lever 135, so that the lever will be yieldably maintained in the desired one of its axially adjusted positions, when the link 208 is once adjusted to proper length, notwithstanding the fact that there is or may be a certain amount of lost motion in the lever adjusting train.

75 The operation of the ribbon mechanism is as follows:

80 When the handle arm of the adjusting lever 187 is pulled forward and engaged in notch 185 of bracket 182, bellcrank 199 is rocked to the position, shown in Figs. 1 and 9 with stop 207 engaging bracket 29, and lever 135 is drawn toward the left and held at the limit of its axial movement in that direction by link 208. In this position of lever 135, pin 176 projects through the enlarged lower end of slot 178 in ear 142 of the lever while pin 175 is withdrawn from slot 177 in ear 141 of the lever. On the down stroke of the character key on any one of the character key levers 19, the lug 17^a on type bar 17 actuated by said key lever engages with the forward edge of universal bar 49 during the last part of the printing stroke of the type bar and pushes the universal bar rearwardly, the parts moving from the position thereof shown in Figs. 9, 13, 14, 15, 16 and 17 to that shown in Figs. 10 and 18 with the upper (usually black) zone of the ribbon interposed between the printing point on the platen and the type at the moment of the type impact.

85 The parts are moved to and positively arrested in this last position as follows: Extension 64^a of the pivot stud which connects the 90

right hand side arm 51 of the universal bar with rock arm 57 pushes rearwardly the reciprocal actuator 154 through engagement of the stud with the rear end of slot 155 in the actuator. Actuator 154 rocks tappet lever 146 to swing tappet 151 forward through the engagement of arm 152 of the lever in slot 153 of the actuator, and tappet 151 rocks lever 135 forward until movements of all parts of the before mentioned type-bar actuated train are arrested at the end of the type bar stroke by stop 136 on lever 135 engaging behind hub 78^a of line space wheel 78.

It will be seen that lever 135 has a fixed extent of throw determined by the universal bar and segment and by stop 136 and hub 78^a. As the pin 176 is engaged in the narrow upper part of slot 178 when lever 135 is arrested and, as the pin fits snugly in this part of the slot, both the bellcrank 124 and the ribbon guide 113 positively connected therewith are positively arrested when lever 135 is arrested, stop 136 and 78^a thus acting to prevent overthrow of the ribbon guide through the positive connecting train from the guide to lever 135. It will be seen from Figs. 10 and 18 that stop 179 on the bellcrank 124 does not move far enough to engage bracket 126 on the short throw of the ribbon guide.

On the rearward stroke of the universal bar the escapement dog rocker is actuated as hereinbefore described to the position shown in Fig. 18 by tappet 96. The rearward movement of ribbon actuator 154 rocks shaft 164 through arms 154 and 170 and connecting link 171 to throw arms 163 forward and rock the ribbon spool rotating pawls 161 through links 162 connecting said pawls with arms 163 to turn the spool on which the ribbon is being reeled. This rocking of shaft 164 swings arm 165 rearward and stretches return spring 159.

On the up stroke of the actuated character key, the several type bar actuated parts of the ribbon mechanism are returned to normal position by the action of springs 159 and 108, assisted somewhat by spring 172 and dog rocker return spring 91, the normal position of the parts of the ribbon mechanism being determined by the abutment of universal bar 49 against the front wall of recess 15 in segment 14. The engagement of stops 134 and 93, which is normally maintained by spring 108 serves to hold the bellcrank and its pins in a predetermined normal position relatively to lever 135 so that said pins may be alternatively engaged with or both disengaged from their coacting slots in actuating lever 135 by axial shifting of the lever which is guided to slide in a predetermined normal plane by rod 30 and the sliding engagement between flat transverse wall 138 of lever 135 and the nose of tappet 151 on lever 146.

To set the vibrating mechanism for the long throw of the guide to use the lower (usually red) zone of the ribbon, hand lever 187 is rocked to the opposite limit of its throw and engaged in locking notch 186 in bracket 182, thereby sliding lever 135 axially toward the right to a position in which pin 175 is engaged in slot 177 of ear 141 of lever 135 and pin 176 is entirely withdrawn from slot 178 in ear 142, this position of the lever 135 being slightly to the right of that shown in Fig. 7 wherein both pins are shown disengaged with lever 187 set as in Fig. 8.

It will be observed that this new connected relation of lever 135 and arm 130 of bellcrank 124 changes the leverage by establishing a motion-transmitting connection between said lever and bellcrank which is nearer to the axis 129 of the bellcrank and farther from the axis 30 of the lever than that established by the previously described setting for the short throw. The increase in effective length of actuating lever 135 and decrease in effective length of the actuated bellcrank arm 130 is such that the guide is given a substantially greater throw from lever 135 in the new setting although lever 135 swings through the same arc on the printing stroke of a type bar and is arrested at the same point by stop 136 striking hub 78^a as the type completes its printing stroke.

The augmented throw of the bellcrank is such that when stops 136 and 78^a engage the lower zone of the ribbon is interposed between the type and platen at the instant of type impact, as shown in Fig. 11. When the guide reaches the position of Fig. 11 pin 175 is engaged in the narrow part of slot 177 of ear 141 and the guide will be held against overthrow by stops 136 and 78^a and the positive connecting train between the guide and lever 135.

As a precaution against possible overthrow of the guide due to increased momentum of the guide and/or the bellcrank on the long throw, stops 179 and 126 are provided, stop 179 on bellcrank forward of the bellcrank axis being adjusted to strike bracket 126 when stops 136 and 78^a engage to prevent possible overthrow of the bellcrank and guide due to any looseness of fit of pin 175 in slot 177.

To render the guide inactive during making of stencils, lever 187 is shifted to its intermediate position and engaged in locking notch 184 as shown in Fig. 8 to slide lever 135 axially to its intermediate axially adjusted position, as shown in Fig. 7, wherein both pins are disengaged from the slotted ears of lever 135. On the printing strokes of the type bars with lever 135 adjusted as just described, all the ribbon actuating devices except bellcrank 124 and guide 113 move as before described, lever 135 swinging forward until stops 136 and 78^a engage, as shown in Fig. 12.

It will be observed from Figs. 7 and 12 that ears 141 and 142 and walls 139 and 140 move forwardly at either side of the outer ends of the pins 175 and 176 and that lever 135 is arrested before wall 138 moves far enough to rock the bellcrank which remains in normal retracted or idle position as does the ribbon guide 113 so that the actuated type strikes the platen at the printing point over 10 the upper edge of the ribbon.

What I claim is:

1. In a typewriting machine, the combination of a bellcrank having a forwardly extending arm and a pendent arm, a ribbon guide connected with the forwardly extending bellcrank arm, a pair of pins projecting laterally from opposite sides of the pendent bellcrank arm at different distances from the axis of the bellcrank, an upstanding actuating lever to the rear of the pendent bellcrank arm mounted at its lower end to swing about an axis parallel with the bellcrank axis and to slide axially relatively to the bellcrank, said lever having a pair of transversely spaced ears at opposite sides of the pendent bellcrank arm each formed with an up and down extending slot in which the adjacent pin is engageable, means for rocking said lever at the type strokes, a stop carried by said lever, a relatively stationary abutment engageable by said stop in the different axially adjusted positions of said lever at every type stroke to positively limit the forward throw of the lever, and manually operable means for shifting said lever axially at will in opposite directions to engage one of said pins with the slot in one of said ears and disengage the other pin from the slot in the other ear.

2. In a typewriting machine, the combination of a bellcrank having a forwardly extending arm and a pendent arm, a ribbon guide connected with the forwardly extending bellcrank arm, a pair of pins projecting laterally from opposite sides of the pendent bellcrank arm at different distances from the axis of the bellcrank, an upstanding actuating lever to the rear of the pendent bellcrank arm mounted at its lower end to swing about an axis parallel with the bellcrank axis and to slide axially relatively to the bellcrank, said lever having a pair of transversely spaced ears at opposite sides of the pendent bellcrank arm each formed with an up and down extending slot in which the adjacent pin is engageable, means for rocking said lever at the type strokes, a stop carried by said lever, a relatively stationary abutment engageable by said stop in the different axially adjusted positions of the lever at every type stroke to positively limit the forward throw of the lever, manually operable means for shifting said lever axially at will in opposite directions to engage one of said pins with the slot in one of said ears and disengage the other pin from the slot in the

other ear, and stopping means cooperative directly with the bellcrank and effective only on the long throw of said bellcrank for preventing overthrow of the vibrator.

3. In a typewriting machine, a platen shift frame movable up and down to change case, a bellcrank pivotally mounted on the shift frame having a forwardly extending arm and a pendent arm, a ribbon vibrator connected directly with the forwardly extending bellcrank arm, a pair of pins carried by the pendent bellcrank arm and projecting laterally therefrom at opposite sides of the arm at different distances from the axis of the bellcrank, a return spring normally rocking the bellcrank in a direction to lower the vibrator, stops on the bellcrank and shift frame for arresting return movement of the bellcrank, an upstanding lever pivotally and axially slidably mounted at its lower end on the shift frame to swing fore-and-aft and slide transversely of the machine, said lever having laterally spaced ears at opposite sides of the pendent bellcrank arm each formed with an up and down extending slot for receiving one of said pins, a transversely extending tappet lever mounted on the shift frame intermediate its ends to swing about an axis perpendicular to the axis of the upstanding lever and having one arm provided with a tappet engaged with said upstanding lever in all axially adjusted positions of the lever, stops on the upstanding lever and shift frame for limiting the forward throw of said lever by the tappet lever, a fore-and-aft reciprocable actuator for the tappet lever mounted on the main frame and provided with an up and down extending slot parallel with the path of movement of the shift frame in which the other arm of the tappet lever is engaged, a universal bar connected with the actuator for reciprocating the same, and means operable at will for sliding the upstanding lever axially in opposite directions to engage one pin with one lever ear and disengage the other pin from the other lever ear.

4. In a typewriting machine, a platen shift frame movable up and down to change case, a bellcrank pivotally mounted on the shift frame having a forwardly extending arm and a pendent arm, a ribbon vibrator connected directly with the forwardly extending bellcrank arm, a pair of pins carried by the pendent bellcrank arm and projecting laterally therefrom at opposite sides of the arm at different distances from the axis of the bellcrank, a return spring normally rocking the bellcrank in a direction to lower the vibrator, stops on the bellcrank and shift frame for arresting return movement of the bellcrank, an upstanding lever pivotally and axially slidably mounted at its lower end on the shift frame to swing fore-and-aft and slide transversely of the machine, said lever

having laterally spaced ears at opposite sides of the pendent bellcrank arm each formed with an up and down extending slot for receiving one of said pins, a transversely extending tappet lever mounted on the shift frame intermediate its ends to swing about an axis perpendicular to the axis of the upstanding lever and having one arm provided with a tappet engaged with said upstanding lever in all axially adjusted positions of the lever, stops on the upstanding lever and shift frame for limiting the forward throw of said lever by the tappet lever, a fore-and-aft reciprocable actuator for the tappet lever 10 mounted on the main frame and provided with an up and down extending slot parallel with the path of movement of the shift frame in which the other arm of the tappet lever is engaged, a universal bar connected with the 15 actuator for reciprocating the same, a spring connected with the upstanding lever for rocking the same rearwardly against the tappet on the tappet lever, means for determining the normal position of the universal bar and 20 actuator, and means operable at will for sliding the upstanding lever axially between two positions in which different ones of said pins are connected with different ones of the lever ears and to an intermediate position in which 25 neither pin is engaged with the lever.

5. In a typewriting machine, the combination of a ribbon vibrator actuating bellcrank, a pivoted line-locking member, and a coil return spring connected at its opposite ends 30 with said bellcrank and member for yieldably holding the bellcrank and line-locking member in their respective normal idle positions.

6. In a typewriting machine having a rotary escapement including an escapement wheel shaft and an escapement wheel held to said shaft to turn therewith and having a hub, the combination of a ribbon vibrator, and key actuated means for operating said 40 vibrator including a lever having two spaced bearings on the escapement wheel shaft and escapement wheel hub respectively and oscillatable thereabout.

7. In a typewriting machine, the combination of a rotary escapement including an escapement wheel shaft extending in an up and down direction and an escapement wheel having a hub held to said shaft, a ribbon vibrator, a bellcrank having a forwardly extending arm connected with the vibrator and a pendent arm, an upstanding actuating lever connected with the pendent bellcrank arm and having a stop arm engageable with the hub of the escapement wheel to limit the forward throw thereof, a tappet lever engaged behind the upstanding lever and having superposed bearings on the escapement wheel shaft and escapement wheel hub respectively 50 for oscillation of said tappet lever there-

about, and key-actuated means for oscillating the tappet lever.

8. In a typewriting machine, the combination of a carriage bed, a rotary escapement including an escapement wheel shaft and an escapement wheel fixed on the shaft and having a hub, an escapement bracket held to the carriage bed, a bearing bushing for the shaft held to said bracket above the wheel, a line-locking latch pivoted on said bushing to turn thereabout, a bell-crane supporting bracket held to the carriage bed forward of the escapement bracket, a ribbon vibrator, a bellcrane pivoted in said bellcrane supporting bracket and having a forwardly extending arm connected with the vibrator and a pendent arm, a coiled return spring connected at its opposite ends with the bellcrane and line-locking latch for lowering the ribbon vibrator and retracting the latch to inactive 70 position, a stop on the bellcrane engageable with the escapement bracket to limit return movement of the bellcrane, an upstanding fore-and-aft swinging lever connected with the pendent arm of the bellcrane for lifting 75 the vibrator, a stop on the upstanding lever engageable with the escapement wheel hub to limit the forward throw of said lever, a tappet lever pivotally mounted on the escapement wheel shaft to oscillate thereabout and engaged behind the up-standing lever, and key-actuated means for oscillating the tappet lever.

9. In a typewriting machine, the combination of a carriage bed, a rotary escapement 100 including an escapement wheel shaft and an escapement wheel fixed on the shaft and having a hub, an escapement bracket held to the carriage bed, a bearing bushing for the shaft held to said bracket above the wheel, a line-locking latch pivoted on said bushing to turn thereabout, a bellcrane supporting bracket held to the carriage bed forward of the escapement bracket, a ribbon vibrator, a bellcrane pivoted in said bellcrane supporting 105 bracket and having a forwardly extending arm connected with the vibrator and a pendent arm, a coiled return spring connected at its opposite ends with the bellcrane and line-locking latch for lowering the ribbon vibrator and retracting the latch to inactive position, a stop on the bellcrane engageable with the escapement bracket to limit return movement of the bellcrane, an upstanding fore-and-aft swinging lever connected with the pendent arm of the bellcrane for lifting the 110 vibrator, a stop on the upstanding lever engageable with the escapement wheel hub to limit the forward throw of said lever, a tappet lever pivotally mounted on the escapement wheel shaft to oscillate thereabout and engaged behind the upstanding lever, a dog rocker pivoted in the escapement bracket to rock in the same direction as the upstanding lever at the type strokes, a coil spring con- 115

- necting the upstanding lever with the dog rocker to hold the upstanding lever to the tappet lever, means for disconnecting the upstanding lever from the bellcrank at will, a universal bar, and connections between the 5 universal bar and said dog rocker and tappet lever for oscillating the rocker and lever at the type strokes.
10. In a typewriting machine, the combination of a main frame, a platen shift frame movable up and down to change case, a ribbon vibrator, means mounted on the shift frame for vibrating the vibrator, including a member adjustable transversely of the machine to vary the throw of the vibrator by 10 means and to render said means ineffective to vibrate the vibrator, universal bar actuated means on the main frame for actuating said vibrator vibrating means on the shift frame, and means for adjusting said 15 member, said last-mentioned means comprising a hand lever pivoted on the main frame at one side of the keyboard of the machine, a fore-and-aft extending bar pivoted at its forward end to said hand lever, means slidably supporting the rear end of said bar on the main frame, a bellcrank pivoted on the shift frame to rock about an up and down extending axis and having a laterally extending 20 arm and a fore-and-aft extending arm, a fore-and-aft extending link connecting said bar and laterally extending bellcrank arm and arranged for equal movement of its rear end above and below a plane perpendicular 25 to the path of shift of the shift frame bisecting the connection of the forward end of the link with said bar, and a transversely extending link connecting the fore-and-aft extending bellcrank arm with said transversely adjustable member of the vibrator vibrating 30 means on the shift frame.
- 40 11. In a typewriting machine, the combination of a main frame, a platen carriage, a shift frame supporting the carriage, a type-bar actuated universal bar having rearwardly extending side arms formed with longitudinal slots at their rear ends, a rock shaft journalled on the main frame, extending through the slots in said side arms, rock arms on said shaft connected with the shift frame, shift-key-operated means for rocking said shaft and arms to shift the shift frame, a fore-and-aft rockable universal bar support mounted on the main frame forward of said rock shaft, pivots connecting the universal bar side arms with said fore-and-aft rockable support, a fore-and-aft extending ribbon actuator connected with one of said pivots adjacent its forward end and having a longitudinal slot in its rear end through which said rock shaft extends, said actuator having a lever-operating slot therein extending parallel with the path of movement of the shift frame, a tappet lever pivoted on the 45 shift frame to swing transversely of the path of movement of the shift frame and having a transversely extending arm slidably engaged in said operating slot in the actuator and also having a transversely extending tappet arm, a fore-and-aft rockable lever pivotally mounted on the shift frame behind which said tappet arm is engaged, a bellcrank pivoted on the shift frame having a pendent arm connected with said fore-and-aft rockable lever and a forwardly extending arm, and a ribbon vibrator connected with the forwardly extending bellcrank arm.
- 50 12. In a typewriting machine, the combination of a main frame, a platen carriage, a shift frame supporting the carriage, a type-bar actuated universal bar having rearwardly extending side arms formed with longitudinal slots at their rear ends, a rock shaft journalled on the main frame extending through the slots in said side arms, rock arms on said shaft connected with the shift frame, shift-key-operated means for rocking said shaft and arms to shift the shift frame, a fore-and-aft rockable universal bar support mounted on the main frame forward of said rock shaft, pivots connecting the universal bar side arms with said fore-and-aft rockable support, a fore-and-aft extending ribbon actuator connected with one of said pivots adjacent its forward end and having a longitudinal slot in its rear end through which said rock shaft extends, said actuator having a lever-operating slot therein extending parallel with the path of movement of the shift frame, a lever pivoted on the shift frame to swing about an up-and-down extending axis and having an arm slidably engaged in said lever-operating slot in the actuator, a ribbon vibrator, and means on the shift frame forming a connection between said vibrator and said lever for vibrating said vibrator and shifting the vibrator bodily with the shift frame.
- 55 13. In a typewriting machine, the combination of a ribbon vibrator, a two-armed lever having one of its arms connected with the vibrator and its other arm provided with two oppositely extending lateral projections, an actuating lever for the two-armed lever having a single arm provided with a flat portion parallel with its axis and two laterally spaced projection-engaging portions cooperative alternately with said projections on the two-armed lever for rocking the latter lever different extents, means slidably and pivotally supporting the actuating lever to swing about an axis parallel with the axis of the two-armed lever and shift bodily sidewise, manually adjustable means for shifting the actuating lever sidewise to operatively connect one of said laterally-spaced projection-engaging portions thereof with one of said projections on the two-armed lever and operatively disconnecting the other projection-engaging portion and projection, and a key-operated tappet cooperative with the said flat portion

of the actuating lever in both axially adjusted positions of the lever.

14. In a typewriter machine, the combination of a main frame, key operated types on the main frame, a platen, a case-shift frame for case shifting the platen up and down, a ribbon guide, means on the shift frame for imparting covering throws of two different extents to the guide, said means including an upstanding lever mounted at its lower end on the shift frame to swing fore-and-aft of the machine to vibrate the guide and slide axially to different transversely adjusted positions in which it is adapted to impart different throws to the guide, a two-armed lever on the shift frame one arm of which swings transversely of the machine, a link extending transversely of the machine and connecting said transversely swinging arm of said two-armed lever with said axially slidable lever adjacent the axis of the latter lever, a manually shiftable adjusting device for the axially adjustable lever mounted on the main frame, and a link connected at one end with said device for endwise movement thereby and connected at its other end with the remaining arm of said two-armed lever, said link arranged for rocking said two arm lever when moved endwise and for swinging up and down during case-shift movements of the shift frame, and means for rocking said axially adjustable lever uniformly fore-and-aft of the machine at the key strokes in all case positions of the platen.
15. In a typewriting machine, the combination of a vibratory ribbon guide, a bellcrank mounted to rock about a horizontal axis which extends transversely of the machine, said bellcrank having a forwardly extending arm directly connected with the ribbon guide and a pendent arm, a key-actuated tappet mounted to rock about an upstanding axis, an upstanding lever interposed directly between the tappet and the pendent arm of the bellcrank for oscillating the bellcrank and rockable about and shiftable along an axis parallel with the axis of the bellcrank, and means for shifting the upstanding lever longitudinally of its axis between two motion-transmitting positions, in both of which it is movable the same extent by the tappet, and in one of which it is operatively connected with the pendent bellcrank arm closer to the axis of the bellcrank than in the other.
16. In a typewriting machine, the combination of a vibratory ribbon guide, a bellcrank mounted to rock about an axis extending transversely of the machine and having a forwardly extending arm connected with the ribbon guide and a pendent arm, an upstanding lever rockable fore and aft of the machine and shiftable transversely of the machine from a position in which it is ineffective on the pendent bellcrank arm to either of two positions in which it is operatively connect-

ed with said arm at different distances from the bellcrank axis, a tappet lever mounted to swing about an upstanding axis and having a contact portion coactive with said upstanding lever the same distance from the axis of the upstanding lever in all adjusted positions of the upstanding lever, and means for vibrating the tappet lever at the key strokes.

17. In a typewriting machine, the combination of a vibratory ribbon guide, a bellcrank having a forwardly extending arm connected with the ribbon guide and a pendent arm and mounted to rock about an axis extending transversely of the machine, a key actuated tappet lever mounted to rock about an up and down extending axis, an upstanding motion transmitting lever interposed directly between the tappet lever and bellcrank, a pivot support parallel with the bellcrank axis upon which the upstanding lever is mounted to rock fore and aft and slide transversely of the machine, and means for sliding the upstanding lever along said support while in operative relation with said tappet lever into either of three positions, in one of which it is operatively disconnected from the pendent bellcrank arm and in the other two of which it is operatively connected with the pendent bellcrank arm different distances from the axis of the bellcrank.

18. In a typewriting machine, the combination of a main frame, a shift frame, a vibratory ribbon guide, a bellcrank supported on the shift frame to rock about an axis extending transversely of the machine and having a forwardly extending arm directly connected with the ribbon guide and a pendent arm, an upstanding lever supported on the shift frame to rock about and shift along an axis parallel with the bellcrank axis from a position in which it is ineffective on the pendent bellcrank arm to either of two positions in which it is operatively connected with said arm at different distances from the bellcrank axis, a tappet mounted on the shift frame to swing about an upstanding axis and having a contact portion coactive with the upstanding lever in all slidably adjusted positions of the upstanding lever, and means on the main frame for vibrating the tappet uniformly at the key strokes irrespective of the case position of the shift frame.

19. In a typewriting machine, the combination of a main frame, a platen shift frame, a platen on the shift frame, a vibratory ribbon guide, a bellcrank pivoted on a transverse axis on the shift frame and having an arm connected with said guide and a pendent arm, a tappet pivoted on the shift frame to vibrate about an upstanding axis, means on the main frame for vibrating the tappet uniformly at the key strokes in all case positions of the shift frame, an upstanding motion-transmitting lever mounted on the shift frame to rock about and shift along an

axis extending transversely of the tappet axis, and key-actuated means extending from the main frame to said upstanding lever for shifting said lever axially to either of two positions in which it is operatively connected with the pendent bellcrank arm different distances from the bellcrank axis.

20. In a typewriting machine, the combination of a main frame, a platen carriage, a platen on the carriage, a case shift frame for the platen carriage, a vibratory ribbon guide, a lever on the shift frame rockable about an axis extending in the direction of shift of the shift frame, means on the main frame reciprocable transversely of the path of shift of the shift frame at the key strokes connected with said lever for sliding of the lever relatively thereto during shifting of the shift frame and for rocking the lever uniformly at the key strokes in all case positions of the shift frame, and means on the shift frame for transmitting motion from said lever to said ribbon guide.

21. In a typewriting machine, the combination of a main frame, a platen carriage, a platen on the carriage, a case shift frame for the platen carriage, a vibratory ribbon guide, a lever on the shift frame rockable about an axis extending in the direction of shift of the shift frame, means on the main frame reciprocable transversely of the path of shift of the shift frame at the key strokes and connected with said lever for sliding of the lever relatively thereto during shifting of the shift frame and for rocking the lever uniformly at the key strokes in all case positions of the shift frame, means on the shift frame interposed between said lever and ribbon guide and settable to impart throws of different amplitude to the guide, and means extending to the main frame for setting said last-mentioned means.

22. In a typewriting machine, the combination of a main frame, a platen shift frame, a ribbon guide, a tappet on the shift frame, guide vibrating means on the shift frame connected with said guide and operable by the tappet, means on the main frame vibrating at the key strokes and directly connected with the tappet for uniformly vibrating the tappet in all case positions of the shift frame, and means for variably setting the guide vibrating means to change the amplitude of throw of the guide at will.

23. In a typewriting machine, the combination of a main frame, a platen shift frame, a ribbon guide, a platen on the shift frame, a key-operated tappet on the shift frame, a pair of directly coactive and relatively adjustable levers one of which is directly connected to the guide and the other directly engaged by the tappet, means for adjusting said levers relatively to each other to two different relations to vary the throw imparted by the tappet engaged lever to the

other lever, a stop on the shift frame for arresting the throw of the tappet engaged lever and always located in the path of said lever, and a limit stop on the shift frame engageable only by the lever connected with the guide and only when said levers are adjusted for the longer throw of the guide.

24. In a typewriting machine, the combination of a main frame, an up and down movable platen shift frame, a platen on the shift frame, ribbon vibrating means on the shift frame including a lever rockable about an upstanding axis which is parallel with the path of movement of the shift frame, and a key-operated actuator mounted on the main frame to reciprocate fore and aft of the machine and having a slot therein extending parallel with the axis of said lever and the path of movement of the shift frame and in which one arm of said lever is engaged.

25. In a typewriting machine, the combination of a main frame, an up and down shifting platen shift frame, a two-arm tappet lever on the shift frame rockable about an axis parallel with the path of movement of the shift frame, a key-operated actuator mounted on the main frame to reciprocate fore and aft of the machine and having a slot extending parallel with the axis of said lever and the path of movement of the shift frame and in which one arm of said lever is engaged, a ribbon guide, and means on the shift frame connected with said guide and operable by the remaining arm of said tappet lever to vibrate the guide up and down.

26. In a typewriting machine, the combination of a main frame, an up and down shifting platen shift frame, a two-arm tappet lever on the shift frame rockable about an axis parallel with the path of movement of the shift frame, a key-operated actuator mounted on the main frame to reciprocate fore and aft of the machine and having a slot extending parallel with the axis of said lever and the path of movement of the shift frame and in which one arm of said lever is engaged, a ribbon guide, means on the shift frame connected with said guide and operable by the remaining arm of said tappet lever to vibrate the guide up and down and means for adjusting said last-mentioned means for varying the throw imparted to the guide.

27. In a typewriting machine having a main frame, a platen carriage shift frame with a transverse tie rod, and an upstanding escapement wheel shaft on the shift frame, the combination of an upstanding lever slidably and pivotally held at its lower end to the tie rod, a tappet lever having a bearing intermediate its ends on said escapement shaft and extending transversely of the machine, means on the main frame connected with one arm of the tappet lever for vibrating the tappet lever uniformly at the key.

strokes in all case positions of the shift frame, the other arm of the tappet lever having a contact head and the upstanding lever having a broad portion disposed in front of 5 said contact head in all slidably adjusted positions of the upstanding lever, a ribbon guide, means on the shift frame operable by the upstanding lever for vibrating the ribbon guide, and means for slidably adjusting 10 the upstanding lever along the tie rod to vary its connection with the guide vibrating means to change the extent of throw of the 15 guide.

28. In a typewriting machine, having a main frame, a platen carriage shift frame 20 movable up and down and having a transverse tie rod, and an upstanding escapement shaft on the shift frame, the combination of an actuator on the main frame reciprocal transversely of the path of movement of the 25 shift frame at the type strokes and having a slot parallel with the path of movement of the shift frame, a tappet lever extending transversely of the machine and having a bearing on the escapement shaft intermediate 30 its ends, said tappet lever having one arm engaged in the actuator slot and its other arm provided with a contact head, an upstanding axially adjustable lever pivotally and slidably mounted on the tie rod and having 35 a broad portion located in front of said contact head in all its adjusted positions, a ribbon guide, a bellcrank pivoted on the shift frame having a forwardly extending arm connected with the guide and a pendent arm, means for axially adjusting the upstanding 40 lever, and means on said pendent arm and the upstanding lever for establishing different motion transmitting connections between the arm and lever in two different adjusted positions of the lever.

29. In a typewriting machine, a ribbon 45 guide, a bellcrank pivoted to rock about an axis extending transversely of the machine and having a forwardly extending arm connected with the guide and a pendent arm having two laterally extending pins at opposite sides thereof different distances from its axis, a rod below and parallel with the bellcrank axis, an upstanding lever having two spaced bearings at its lower end on said rod for rocking about and sliding along the rod and two transversely spaced ears at opposite sides of the pendent bellcrank arm each provided with an up and down extending slot, 55 said ears being spaced for engagement of one of said projections at a time in an ear slot and for simultaneously disconnection of both ears from said projections, means for sliding the upstanding lever along said rod, a stop having a fixed relation to the axis of the upstanding lever, a transversely extending stop arm on said lever above the rod and movable 60 into contact with said stop on the down strokes of the keys in all axially adjusted 65

positions of the lever, and a key operated tappet having a contact head in rear of said lever, said lever having a contact portion above said rod sufficiently wide transversely of the machine for engagement therewith of 70 the tappet head in all axially adjusted positions of the lever.

30. A typewriting machine having an escapement dog rocker and a ribbon vibrating means including a swinging tappet-actuated member, said dog rocker and member swinging about parallel axes and having parts which move in the same direction on the down strokes of the keys and are connected by a coiled spring holding the member to its actuating tappet.

In testimony whereof I hereunto affix my signature.

HENRY ALLEN AVERY.
